UNITED STATES PATENT OFFICE.

CAMPBELL MACMILLAN, OF SCHENECTADY, NEW YORK, ASSIGNOR TO GENERAL ELECTRIC COMPANY, A CORPORATION OF NEW YORK.

MULTISPEED INDUCTION-MOTOR.

1,356,934.

Specification of Letters Patent. Patented Oct. 26, 1920.

Application filed May 31, 1917. Serial No. 171,915.

To all whom it may concern:

Be it known that I, CAMPBELL MACMILLAN, a citizen of the United States, residing at Schenectady, county of Schenectady, 5 State of New York, have invented certain new and useful Improvements in Multi-speed Induction-Motors, of which the following is a specification.

My invention relates to multi-speed induction motors and has for its object the provision of an improved multi-speed induction motor. My invention more particularly relates to multi-speed induction motors of the type described in my copending 15 application for Letters Patent of the United States, Serial No. 171,916, filed May 31, 1917. In this connection, the object of my invention is to provide an induction motor having a primary winding with simplified 20 connections for producing substantially sinusoidal or balanced primary magnetic fields of different pole numbers when connected to polyphase systems of energy distribution of different numbers of phases. 25 Other objects of the invention will be brought out in the course of the following description.

I have described in my aforementioned application a multi-polar induction motor 30 having a primary winding arranged to produce primary magnetic fields of different pole numbers when suitably connected to polyphase systems of energy distribution of different numbers of phases. I particularly 35 described a primary winding arranged to produce primary magnetic fields of either n or $2n$ poles when suitably connected to a polyphase system of three-phase electro-motive forces and a primary magnetic field 40 of $\frac{3n}{2}$ poles when suitably connected to a polyphase system of quarter-phase electro-motive forces. The particular aim of my present invention is to provide a more simple 45 arrangement for effecting the necessary circuit connections in such a combination comprising a source of polyphase energy of different phase numbers and a multi-speed induction motor adapted to be connected thereto to produce different pole 50 numbers of its primary winding.

To this end I propose to connect all coil sections or phase belts which are in the same phase when the primary winding is arranged 55 for one pole number to a common

neutral, and, considering the opposite ends of all coil-sections, to connect those coil-sections which are in the same phase when the primary winding is arranged for the second pole number to a common neutral. The 60 common connections at one end of the coil-sections then serve as terminals for one pole number of the primary winding and the common connections at the other end form a complete set of neutral or Y-points, while 65 for the other pole number the latter common connections serve as terminals and the first mentioned common connections form a complete set of neutral points.

The novel features of the invention which 70 I believe to be patentable are definitely set forth in the appended claims. The principle of the invention, together with the construction and mode of operation of induction motors and systems embodying the 75 same, will be best understood from the following description taken in conjunction with the accompanying drawings, in which:

Figure 1 is a diagrammatic assembly of 80 a system of electric ship propulsion embodying the present invention; Fig. 2 is an explanatory legend-diagram; Fig. 3 is a diagram of the electrical connections of the system of Fig. 1; Figs. 4 and 5 are explanatory vector diagrams; Figs. 6 and 7 are explanatory 85 diagrams of the different connections of the motor shown in Figs. 1, 2 and 3; Fig. 8 is a diagrammatic view of a modified form of the invention; Fig. 9 is a diagrammatic view of a further modification 90 of the invention; Figs. 10, 11 and 12 are explanatory diagrams of the different connections of the primary winding of the motor represented in Fig. 9; Fig. 13 is a diagrammatic view of another modification of the 95 invention; and Fig. 14 is an explanatory diagram.

The present invention is of particular advantage in electric systems of ship propulsion, and in Fig. 1 I have illustrated such a 100 system comprising an elastic-fluid turbine 15 directly coupled to an alternating current generator 16. A multi-speed induction motor 17 has its rotor mounted on the shaft 18 of one of the ship's propellers 19. It will 105 of course be understood that the entire equipment will generally consist of a plurality of propellers and induction motors, and usually will include two or more turbine-driven generators 15—16. The pro- 110

eller-driving motor 17 is designed for pole-changing in order to provide two efficient speed ranges of navigation. In accordance with my present invention, the primary winding of the motor 17 is provided with very simple connections for producing primary magnetic fields of two different pole numbers when supplied by the generator 16 with polyphase systems of energy distribution of different phase numbers.

The primary winding of the so-called three-phase induction motor is usually wound six-phase with six coil-sections or phase-belts per pair of poles. This result is obtained by providing per pair of poles two phase-belts in which the direction of current flow is relatively opposite or displaced by 180 electrical degrees corresponding to each of the three phases of the source of supply. The currents in adjacent phase-belts are then displaced in phase by 60 electrical degrees, and the winding may be called a 60° six-phase primary winding. Such a winding is diagrammatically represented by the first row of legends $a, b, c, \bar{a}, \bar{b}, \bar{c}$ of Fig. 2, where it is designated " n -poles 6° ". The letters a and $\bar{a}$ represent the phase-belts or coil-sections connected to phase A and in which the currents are relatively opposite in direction or 180 electrical degrees out of phase, b and $\bar{b}$ represent the corresponding phase-belts connected to phase B, and c and $\bar{c}$ the corresponding phase-belts connected to phase C. All of the phase-belts of the same phase may be electrically connected together in any suitable manner, for example, in series, in parallel, or partly in series and partly in parallel, as will be understood by those skilled in the art.

The second row of legends in Fig. 2 represents the arrangement of the phase-belts $p, \bar{p}, q$ and $\bar{q}$ of a $\frac{3n}{2}$ -pole quarter-phase primary winding, where each phase-belt has the same number of coils as the phase-belts of the n -pole winding just described. In the drawings, the phase-belts $p, \bar{p}, q$ and $\bar{q}$ are, therefore, positioned directly beneath the phase-belts $a, \bar{a}, b, \bar{b}, c, \bar{c}$ of the n -pole winding.

The vertical lines directly beneath the two rows of legends just described will now be assumed to represent the centers of the coil-sections or phase-belts of the primary winding of a motor embodying my present invention. The primary winding will be of the multiple layer drum type and will usually be a 100 per cent. pitch for $\frac{3n}{2}$ -poles, winding are 100 per cent. pitch for n -poles, they will be 66 $\frac{2}{3}$ per cent. pitch for n -poles.

The relative pitch of the primary coils under the two different polar arrangements is chosen so as to give the most favorable compromise pitch for both arrangements, considering of course the particular conditions under which the motor is to operate. The two rows of legends above the vertical lines then represent the phases to which the coil-sections or phase-belts represented by the vertical lines are connected for the corresponding polar arrangements, and indicate the particular electrical changes which each phase-belt must undergo in passing from one polar arrangement to the other. The phase-belts which undergo the same electrical change in passing from one polar arrangement to the other may be electrically connected in a single group, and it will be seen from an inspection of Fig. 2 that there will be twelve of such groups. These groups are designated by the legends beneath the vertical lines to indicate the particular changes in their connections when the pole numbers of the primary winding are changed. Thus, group ap is connected to phase A for the n -pole arrangement and to the positive terminal of phase P for the $\frac{3n}{2}$ -pole arrangement; group $\bar{b}q$ is connected to phase B so as to carry current 60 electrical degrees out of phase with the current in phase-belt a for the n -pole arrangement and to the positive terminal of phase Q for the $\frac{3n}{2}$ -pole arrangement; group $\bar{c}p$ is connected to phase C so as to carry current 120 electrical degrees out of phase with the current in phase-belt a for the n -pole arrangement and to the negative terminal of phase P for the $\frac{3n}{2}$ -pole arrangement, and so on.

In accordance with my present invention the phase-belts or coil-sections which are in the same phase for the n -pole arrangement are connected at one end to a common terminal or neutral. Thus, all of the a and $\bar{a}$ coil-sections are connected to the common terminal A, the coil-sections b and $\bar{b}$ are connected to the common terminal B, and the coil-sections c and $\bar{c}$ are connected to the common terminal C. At their other ends, the coil-sections are similarly connected to common terminals or neutrals corresponding to the $\frac{3n}{2}$ -pole arrangement. Thus, all of the coil-sections p are connected to the terminal P and coil-sections $\bar{p}, q$ and $\bar{q}$ are connected to terminals $\bar{P}, Q$ and $\bar{Q}$, respectively. When three-phase currents are supplied to the terminals A, B and C, the coil-sections of the entire primary winding will be arranged as an n -pole, six-phase, four-circuit star-connected winding, and

when quarter-phase currents are supplied to the terminals P , $\bar{P}$, Q and $\bar{Q}$, the primary winding will be arranged as a $\frac{3n}{2}$ -pole, quarter-phase, three-circuit diametrical winding.

These circuit arrangements will be more clearly seen after a discussion of Fig. 3.

The electrical connections of the system of Fig. 1 are shown in Fig. 3. The primary winding of the motor is divided into twelve circuits or groups, just as explained in connection with Fig. 2. These groups are designated by the same legends as in Fig. 2. The common terminals or neutrals are likewise designated by the same reference letters as in Fig. 2. The armature winding of the generator 16 has four coil-sections 40, 41, 42 and 43, which are 60 electrical degrees apart, and four coil sections 44, 45, 46 and 47, which are 30 electrical degrees apart. The eight coil-sections of the armature winding are connected to a combined phase-changing and pole-changing switch 21. This switch has five double-throw blades. In its lower position it connects the armature circuits of the generator as a three-phase star-connected winding to the three-phase terminals A , B and C . The vector diagram of the generator winding for this connection is represented in Fig. 4, where the vectors are designated by the same reference characters as the corresponding coil-sections of Fig. 3. The connections of the twelve groups of the primary winding of the motor for this position of the switch 21 are shown in Fig. 6. When the switch 21 is thrown to its upper position, the armature circuits of the generator are connected as a two-circuit independent quarter-phase winding to the quarter-phase terminals P , $\bar{P}$, Q and $\bar{Q}$. The vector diagram of the generator winding for this connection is represented in Fig. 5, and the connections of the primary winding of the motor are shown in Fig. 7.

It will be observed that the switching mechanism for pole-changing becomes very simple by the use of my present invention. Only seven terminals are brought out from the multi-polar induction motor. The quarter-phase terminals are provided with a reversing switch 22, since in ship propulsion reversal will only be carried out with the low speed polar arrangement, that is with $\frac{3n}{2}$ -poles.

In Fig. 8 of the drawings, I have shown a multi-polar motor adapted to be supplied with polyphase systems of energy distribution of three and six phases. Following the procedure outlined in Fig. 2, it will be evident that in the most general case of n and m primary magnetic poles, the primary winding must be divided into eighteen cir-

cuits or groups. The phase-belts for the three-phase arrangement I will designate a , b , c and for the six-phase arrangement a , $\bar{b}$, c , $\bar{a}$, $\bar{b}$, $\bar{c}$, and the eighteen groups are designated by characteristic legends following the system used in Fig. 2. All of the phase-belts a for the n -pole three-phase arrangement are connected at one end to a common terminal A , and similarly with respect to phase-belts b and c . The other ends of the phase-belts are connected to six terminals so that the same phase-belts for the m -pole six-phase arrangement are connected to the same terminals. The motor, accordingly, has only nine terminals. The armature winding 26 of the supply generator is delta-connected for three-phase and diametrical for six-phase. A single switch 27 with six double-throw blades effects the necessary changes in the generator and motor circuits for changing from n to m poles, or vice versa. When this switch is in its lower position, the generator is three-phase delta-connected to the motor terminals A , B and C and the primary winding of the motor produces a primary magnetic field of n -poles. When the switch 27 is in its upper position, the generator is connected to deliver six-phase electromotive forces to the motor terminals a' , $\bar{b}'$, c' , $\bar{a}'$, $\bar{b}'$, and $\bar{c}'$, and the primary winding produces m poles.

The multi-polar motor of my present invention may have a secondary winding of any suitable type. The simplest type of secondary winding would be a low resistance squirrel cage winding, but for installations where speed control or increased torque is desired the secondary winding may be phase-wound and arranged for connection to an external resistance. Where increased torque for particular conditions of operation are required, as for reversing in ship propulsion, a double squirrel cage secondary winding may be of advantage, as explained in Letters Patent of Ernst F. W. Alexander, No. 1,215,095, patented Feb. 6, 1917. Increased torque of the motor may also be obtained in the manner described in my co-pending application for Letters Patent of the United States, Serial No. 171,917, filed May 31, 1917. Such a modification of the present invention is illustrated in Fig. 9.

The row of short heavy vertical lines in Fig. 9 represents the centers of coil-sections or phase-belts of the primary winding of a multi-speed induction motor, as described in connection with Fig. 2. In the motor of Fig. 9, n is equal to 16 and $\frac{3n}{2}$ is equal to 24. In addition, the coil-sections of this winding are arranged to be connected as a 32-pole three-phase primary winding. The arrangement of the coil-sections for this 32-pole connection is represented by the last row of legends a , $\bar{b}$, c , a , etc.

The polyphase systems of energy distribution of different numbers of phases are produced by a generator whose armature winding 22 is a three-phase star-connected winding. One phase winding of the generator is divided into two sections 60 electrical degrees apart. The circuits of the winding 22 are connected to a generator phase-changing switch 23 in such a manner that a polyphase system of three-phase electromotive forces is produced when the switch is in its right-hand position and a polyphase system of quarter-phase electromotive forces is produced when the switch is in its left-hand position. The armature winding 22 of the generator is star-connected for the three-phase system and connected in diametrical independent circuits for quarter-phase. The generator switch 23 is a five-unit double-throw switch and in changing the generator circuits from three-phase to quarter-phase alters the voltage per phase of the generator in the ratio of 1 to 0.71. In other words, the terminal voltage of the generator when furnishing quarter-phase electromotive forces is 71% of its terminal voltage when furnishing three-phase electromotive forces.

In accordance with the principle of my present invention, all of the phase-belts *a* with respect to the 32-pole arrangement are connected at one end to a common terminal A, and the phase-belts *b* and *c* are similarly connected to common terminals B and C, respectively. Considering now the 24-pole quarter-phase arrangement, all of the phase-belts *p* are connected at their other ends to a common terminal P, and all of the phase-belts *p̄* are similarly connected to a common terminal *P̄*. The common terminal Q is made up of three terminals *a'*, *b'*, *c'*, and the common terminal *Q̄* is similarly made up of three other terminals *a'*, *b'*, *c'*. A four-unit double-throw switch 24 is provided for connecting the three terminals *a'*, *b'*, *c'* of terminal Q together and the three terminals *a'*, *b'*, *c'* of terminal *Q̄* together when the switch is in its lower position. When the switch is in its upper position, it connects the two terminals *a'* and *a'* together, and similarly the two terminals *b'* and *b'* and *c'* and *c'*.

A second motor switch 26 is provided. In its right-hand position this switch connects the three-phase supply system to the motor terminals A, B, C, and in its left-hand position it connects the three-phase supply system to the motor terminals *a'*, *b'*, *c'*.

The manipulation of the switches 23, 24 and 26 to effect the different operating conditions of the system is as follows: For 24-pole quarter-phase operation of the motor, the switch 23 is thrown to its left-hand

position and the switch 24 is in its lower position. The groups or coil-sections of the primary winding of the motor are arranged as indicated in Fig. 10 for this polar arrangement. For the 16-pole six-phase operation of the motor, the generator switch 23 is thrown to its right-hand position, and the motor switches 24 and 26 are thrown to their lower and right-hand positions, respectively. The groups of the motor winding 75 are then arranged as indicated in Fig. 11. For the 32-pole three-phase operation of the motor, the generator switch 23 is in its right-hand position, and the motor switches 24 and 26 are in their upper and left-hand 80 positions, respectively. The arrangement of the motor circuits for 32 poles is shown in Fig. 12. It will be observed that these three polar arrangements are obtained with only eleven motor terminals. The twelve groups 85 of the motor winding are designated in Figs. 10, 11 and 12, by characteristic legends *ap*, *aq*, etc., to designate the changes in the connections of the groups for the three different 90 polar arrangements. These characteristic legends are derived from the legends of Fig. 9, as will be clearly understood in view of preceding explanations.

In accordance with the invention of my aforementioned application Serial No. 171,917, the primary winding of the motor represented in Fig. 9 is divided into two components such that when one component is disconnected from the source of supply 100 alternate sections embracing 4, 6 or 8 poles, according as the primary winding is connected for 16, 24 or 32 poles, are idle or inactive. To this end switches 25 are associated with the eleven terminals of the motor 105 so as to disconnect these alternate sections of the primary winding from the source of supply. A compound or double secondary winding is provided, one section of which is of low resistance and the other section of high resistance. In Fig. 9 of the drawings, I have shown a high resistance squirrel cage winding 20 and a low resistance secondary winding 31 arranged so that when alternate sections of the primary winding 110 are inactive or idle secondary currents will flow in circuits including conductors corresponding to both active and idle sections of the primary winding, whereby the conductors of the high resistance winding 20 115 which are adjacent current-carrying conductors corresponding to idle sections of the primary winding are included by transformer action as a part of the secondary winding of the motor.

The coils of the winding 31 are connected to two sets of collector rings 33 and 34 so that with respect to 24 primary magnetic poles this secondary winding has twelve circuits connected in parallel between the 120

5 collector rings 33 and similarly twelve circuits connected in parallel between the rings 34. For the sake of clearness, only the connections to the collector rings 33 have been
 10 fully indicated in the drawings. Every coil or group of coils beneath phase-belts p and $\bar{p}$ are connected in series to the similarly positioned coil or group of coils six poles removed with respect to the 24-pole ar-
 15 rangement, and the terminals of these series-connected coils or groups of coils are connected to the collector rings 33. The coils beneath phase-belts q and $\bar{q}$ are similarly connected to the collector rings 34. For the
 20 motor of 24 poles, there will, therefore, be twelve of these series-connected coils or groups of coils connected to each set of collector rings 33 and 34. The transformer action between the low resistance winding
 25 31 and the high resistance squirrel cage winding 20 is obtained by open-circuiting alternate sections of the primary winding embracing six adjacent poles.

It will be observed that the low resistance
 25 secondary winding 31 is effectively open-circuited for a primary magnetic field of 24 poles. This winding might, therefore, remain entirely inactive for this polar ar-
 30 rangement and all of the secondary cur-
 35 rent would then be forced to flow in the high resistance winding 20. Generally, however, it will be more desirable to provide external resistances 35 arranged to be con-
 40 nected between collector rings 33 and 34, respectively, and thus to complete the cir-
 45 cuits of the winding 31. The resistances 35 may be adjustable and when entirely cut out so as to short-circuit the rings 33 and 34, respectively, the winding becomes electric-
 50 ally equivalent to an externally short-circuited low resistance winding.

Although the winding 31 is effectively open-circuited for 24-poles, it is internally short-circuited for either 16 or 32 poles.
 45 For the 16-pole arrangement, the coils beneath phase-belts a , b and c are connected to the collector rings 33 to form in effect a short-circuited star-connected winding and the coils beneath phase-belts $\bar{a}$, $\bar{b}$ and $\bar{c}$ are
 50 similarly connected to the collector rings 34. For the 32-pole arrangement, the winding is similarly a short-circuited, star-connected winding. The only difference between the short-circuits for the 16- and 32-pole ar-
 55 rangements is that for 32 poles the "p" and "q" circuits connected to the collector rings 33 and 34, respectively, carry currents in the same direction, while for 16 poles the currents in these "p" and "q"
 60 circuits are 180 electrical degrees apart.

In Fig. 13 of the drawings, I have repre-
 65 sented a modified arrangement of connec-
 70 tions for such a system as illustrated in Fig.
 75 9. The two 120 degree (or 60°) circuits

80 of the generator winding 27 are independent 65 and have two terminals each brought out to a six-unit generator switch 28. The two 30 degree (or 150°) circuits of the generator winding are also independent and their four terminals are brought out to the switch 70 28. A five-unit double-throw switch 29 is also provided. The phase-belts p , $\bar{p}$, q and
 75 $\bar{q}$ of the $\frac{3n}{2}$ -pole arrangement of the motor are connected to common terminals P , $\bar{P}$, Q and $\bar{Q}$, just as in the preceding modifi-
 80 cations. The phase-belts of the motor winding are connected at their other ends to six common terminals A , B , C , $\bar{A}$, $\bar{B}$ and $\bar{C}$. All of the phase-belts a for the n -pole arrangement are connected to the common terminal A , phase-belts $\bar{b}$ are connected to terminal $\bar{B}$, and so on. The motor thus has only ten terminals for obtaining three dif-
 85 ferent polar arrangements.

The manipulation of the switches 28 and 90 29 for obtaining the different combinations of the system is as follows: For $\frac{3n}{2}$ -poles 90 with a quarter-phase source of energy, the switch 29 is in its "off" position and the switch 28 is in its left-hand position. The arrangement of the twelve groups of the primary winding is then substantially the 95 same as in Fig. 10, the only difference being that the neutral point connections shown in Fig. 10 are not made in the motor of Fig. 13. For n -poles, the switch 28 is thrown to its right-hand position, and the 100 switch 29 is thrown to its left-hand position. The twelve groups of the primary winding are arranged for this connection substantially the same as represented in Fig. 11. For $2n$ -poles, the switches 28 and 29 are both 105 in their right-hand positions, and one ter-
 110 minal (A) of each phase winding of the generator is connected to the alternate cor-
 115 responding phase-belts (a) of the motor, while the other terminal ($\bar{A}$) of the same generator phase winding is connected to the other corresponding phase-belts (a) of the motor. A diagram of the electrical connec-
 120 tions of the generator and motor circuits for $2n$ -poles is shown in Fig. 14 of the draw-
 125 ings. The same rotor as illustrated in Fig. 9 may be used with the motor of Fig. 13.

I have herein shown and particularly de-
 130 scribed certain embodiments of my inven-
 135 tion for the purpose of explaining its prin-
 140 ciple and showing its application, but nu-
 145 merous modifications of the details of con-
 150 struction and arrangement of these embodi-
 155 ments and other applications will present
 160 themselves to those skilled in the art. I, 165 therefore, wish to cover by the following
 170 claims all modifications within the spirit
 175 of the invention.

What I claim as new and desire to secure by Letters Patent of the United States, is:—

1. A multi-speed induction motor having a primary winding arranged so as to produce balanced primary magnetic fields of n and $\frac{3n}{2}$ pole numbers when supplied from three-phase and quarter-phase systems of energy distribution respectively, said primary winding comprising a plurality of circuits each of which contains conductors which carry current relatively in the same direction when the primary winding is connected for either one of said different pole numbers, said circuits being permanently connected for the n and $\frac{3n}{2}$ pole numbers so that all the ends thereof, which are to be connected to the same phase of the three-phase system for n pole numbers, are connected together while the opposite ends thereof, which are to be connected to the same phase of a quarter-phase system for $\frac{3n}{2}$ pole numbers, are connected together.
2. A multi-speed induction motor having a primary winding arranged so as to produce balanced primary magnetic fields of n and $\frac{3n}{2}$ pole numbers when supplied from three-phase and quarter-phase systems of energy distribution respectively, said primary winding comprising a plurality of circuits each of which contains conductors which carry current relatively in the same way when the primary winding is connected for either one of said different pole numbers, said circuits being connected together so that all circuits which are to be connected to the same phase of a three-phase system for n pole numbers are permanently connected together at one end while the opposite ends of said circuits are connected so that all circuits which are to be connected to the same phase of a quarter-phase system for $\frac{3n}{2}$ pole numbers are permanently connected together.
3. A multi-speed induction motor having a primary winding arranged so as to produce balanced primary magnetic fields of n and $\frac{3n}{2}$ pole numbers when supplied from three-phase and quarter-phase systems of energy distribution, said primary winding comprising a plurality of circuits each of which contains conductors which carry current relatively in the same direction when the primary winding is connected for either one of said different pole numbers, said circuits being permanently arranged for the n and $\frac{3n}{2}$ pole numbers so that there are three and four terminals respectively for the n

and $\frac{3n}{2}$ pole numbers of the primary winding which respectively form neutral points for the $\frac{3n}{2}$ and n pole numbers of the primary windings.

4. A multi-speed induction motor having a primary winding arranged so as to produce balanced primary magnetic fields of n and $\frac{3n}{2}$ pole numbers when supplied from three-phase and quarter-phase systems of energy distribution respectively, said primary winding comprising a plurality of circuits each of which contains conductors which carry current relatively in the same way when the primary winding is connected for either one of said different pole numbers, said circuits being permanently connected together so that there are three and four terminals respectively for the n and $\frac{3n}{2}$ pole numbers of the primary winding which respectively form neutral points for the $\frac{3n}{2}$ and n pole numbers of the primary winding.

5. A multi-speed induction motor having a primary winding of the multiple layer drum type adapted to be connected as an n pole six-phase and as a $\frac{3n}{2}$ pole quarter-phase winding when supplied from three-phase and quarter-phase systems of energy distribution, said primary winding having terminals, the number of which does not exceed the sum of the numbers of phases of said different polyphase systems, and means for changing the connections of said terminals so as to arrange said primary winding for said different pole numbers and for connection to different polyphase systems of distribution.

6. A system of energy distribution comprising in combination a generator having a winding adapted to be connected to deliver either quarter-phase or three-phase alternating electromotive forces, a multi-speed induction motor having a primary winding of the drum type adapted to be connected as an n -pole six-phase winding and as a $\frac{3n}{2}$ pole quarter-phase winding and as a $2n$ -pole three-phase winding, said primary winding having less than twelve terminals, and means for controlling the connections of the generator winding and the connections between said terminals and the generator arranged to connect the terminals of said primary winding to said source so as to produce any one of said polar arrangements of said primary winding.

7. A multi-speed induction motor having a primary winding of the multiple layer

drum type comprising twelve circuits, each of said circuits containing those conductors which carry current relatively in the same way when the primary winding is arranged
5 as an n -pole six-phase winding or as a $\frac{3n}{2}$ pole quarter-phase winding or as a $2n$ -pole three-phase winding, said circuits being permanently connected together so that the
10 primary winding of the motor has less than twelve terminals, and means for connecting said terminals so that said primary winding is arranged to produce n or $2n$ primary magnetic poles when connected to a three-phase source of alternating current energy
15 and so as to produce $\frac{3n}{2}$ primary magnetic poles when connected to a quarter-phase source of alternating current energy.

8. A multi-speed induction motor having 20 a primary winding of the multiple layer drum type comprising twelve circuits, each of said circuits containing those conductors which carry current relatively in the same way when the primary winding is connected 25 for any one of three different pole numbers, said circuits being permanently connected together so that the primary winding of the motor has less than twelve terminals, and means for connecting said terminals so that 30 said primary winding is arranged to produce primary magnetic fields of three different pole numbers when suitably supplied with alternating current energy.

In witness whereof, I have hereunto set 35 my hand this 29th day of May, 1917.

CAMPBELL MACMILLAN.
